CARBURETOR

Application filed November 30, 1925. Serial No. 72,354.

The present invention relates to a carburetor for motor cars, particularly for the "Ford" engine, in which various advantages in comparison with the hitherto known constructions are attained. Furthermore, the carburetor is simple in design, and ensures a great saving in fuel.

The carburetor is U-shaped, and the one branch lies up against and alongside the exhaust pipe, towards which it has an elongated slot opposite the petrol inlet, so that the petrol sucked through a nozzle in the carburetor pipe as well as the air in this pipe are heated by means of the heat from the exhaust pipe, being at the same time atomized.

In connection with the fuel throttle valve in the carburetor pipe in front of the supply pipe of the engine, there is a valve for regulating the supply of air for the petrol sucked into the carburetor pipe, allowing an automatically adjusted current of air corresponding to the position of the throttle valve and the supply of fuel, thus allowing a careful mixture of fuel.

The petrol drawn from the main tank is first carried to an intermediate tank, from which it is sucked into the carburetor pipe, and in which there is always collected sufficient petrol to start the engine and keep it running a short while, it being in this manner unnecessary to draw the petrol from the main tank. The engine is therefore easy to start and the usual vacuum tank eliminated.

The invention is illustrated in the accompanying drawing, where

Fig. 1, is a side view of the complete carburetor,

Fig. 2, a part of the lower branch of the carburetor showing the regulating means arranged thereon,

Fig. 3, a top view of the carburetor,

Fig. 4, a longitudinal section of the air throttle valve on an enlarged scale, and

Fig. 5, a cross section through line A—B in Fig. 1, on an enlarged scale.

The U-shaped carburetor pipe 1 lies with the one branch 1^a close up to and alongside the exhaust pipe 2, indicated with dotted lines, towards which it is provided with a somewhat elongated slot 3, through which the heat

from the exhaust pipe 2 enters the pipe 1^a. Upon the opposite side of the latter and attached to the dashboard 4 of the car or to any other suitable place, is an intermediate tank 5 to which the petrol from the main tank is carried through a side tap 6. Within the intermediate tank 5 is lowered the vertical portion of a bent pipe 7, which at its lower end has slits 8 for the petrol, and near the pipe 6 a very small suction opening 9 for air from the upper part of the tank. The pipe 7 is fastened to a flange 11 upon the tank 5 by means of a nut 10, and immediately above this bent to a downward incline. The lower end of this pipe is secured to an elbow 13 by means of a nut 12, and this elbow enters a tap 14 on the carburetor pipe 1^a provided with a nozzle. During the suction of the engine the petrol passes as a fine spray through this nozzle from the intermediate tank 5, though this tank is situated higher than the main tank, as the upper chamber of the tank is evacuated through the opening 9, and thus acts as a kind of vacuum tank.

The branch 1^a of the carburetor pipe is continued to form a slotted guide housing 15 for a partly conical valve body 16, Fig. 3, which closes a corresponding aperture 17 within the branch 1^a. The rear cylindrical portion of the said valve body is hollow and contains a coil spring 18, the one end of which is attached to the end of an angle lever 19, which enters the hollow portion of the valve body through a slot 20. The rear wall of the valve body is provided with an air hole 21, and at its rear end an eye 22 for connection with a handle rod, not illustrated, by means of which it is possible to close the valve by hand when the engine is to be started, as the spring 18 is then pressed together against the rod 19 without moving the latter.

The opposite end of the rod 19 is connected to move with the angle shaped shaft 23 for the usual throttle valve 25 in the lower carburetor branch 1^b in front of the suction pipe 24. The throttle valve 25 can be turned by means of an arm 26 attached to the said shaft from the driver's seat. The shaft 23 may furthermore be surrounded by a bearing 27 at-

tached to any suitable rigid portion of the engine.

It will be understood that simultaneously with the regulation of the throttle valve 25 to supply more or less fuel to the engine, the air valve body 16 is regulated, thus regulating the supply of air through the aperture 17 to the carburetor pipe to conform exactly with the quantity of fuel sucked into the engine; it is therefore possible by repeated trials to form the connection with the air valve in such a manner that the engine can work with as weak a mixture as in any way possible. Partly for this reason, and partly on account of the great heating attained through the elongated slot 3 and the resulting atomizing, the engine consumes only a minimum of petrol during the driving.

As indicated in Fig. 3, there can be attached, within the branch 1^a opposite the slot 3 and bent towards the exhaust pipe 2, a rail or tongue 28, against which the fuel mixture is thrown back before it returns through the pipe 1, 1^b to the engine, and this further assists the atomizing and vaporization of the fuel.

Having now described my invention, what I claim is:

A petrol carburetor for internal combustion engines, comprising a U-shaped carburetor pipe having one branch for the inlet of fuel and air, provided with an elongated slot for arrangement against and alongside the exhaust pipe of the engine so that part of the surface of the pipe is exposed to the interior of the branch, an inlet jet for fuel opposite the slot, an inlet for air, a valve body to control said air inlet, the other branch of said pipe being arranged to be connected to the motor inlet manifold and being provided with a mixture throttle valve, said air valve and said mixture throttle valve being operatively connected together so that when the air and throttle valves are open motor suction draws fuel through the inlet as a fine spray and atomizes same and also draws in air which together with the fuel is heated due to the exposed surface of the exhaust pipe, the said interconnected valve body and throttle providing a means whereby the supply of air is regulated to conform with the consumption of fuel, and said branch having a baffle arranged therein opposite the elongated slot, and against which baffle the fuel impinges, thus being further atomized before passing through the carburetor pipe to the motor.
